Otis Tufts

The Schedule referred to in the Yellow Patent and making part of the same containing a description in the words of the said Otis Tufts himself of his improvement in the Rolling Chisel. All persons to whom these presents shall come
the Chisel of the City of Boston & in the County of Suffolk
& Commonwealth of Massachusetts (Mechanician named
Presting). Be it known that I the said Otis Tufts have invented, constructed, made, and applied to use a new and useful improvement in the machine called the Rolling Chisel. My improvement consists of a combination of two chisels in a manner and withal arranged for the purpose of straightening the progressive or toggle jointed lever by an easy and nearly uniform pull. The machinery is simple and moves with little strain or friction. It moves the pitman in nearly in a right-line with the motion of the progressive or toggle jointed lever on which it operates to give the impression, and while the working lever is away part of the pull is moved by a strength best adapted to the power and convenience of the operator, the power at the point of the impression, may be of almost any desired degree. I use the frame, bed-plate, pattern, progressive or toggle jointed lever, and spiral springs nearly in the common manner in which the same are used in traps generally. My combination which is for the purpose of driving the pitman on to the progressive lever to make it straight, employs only the working or hand lever, the pitman or driving lever, the friction roller, and the other apparatus, by which the pitman is made to bear & operate on the progressive lever. Every part of the machinery, I use, has been before used, separately, & for the purpose. But the combination I claim herein, is concrete to my invention, & it may be confidential.

employed instead of the existing machinery to increase the impression in the backfire wood. My improvement is represented in two drawings on plates which accompany this specification and are made a part of it. Plate No 1 is a perspective drawing of so much of the printing frame or press with the platen, back plate & other machinery as is necessary to exhibit & explain my invention, and this is drawn on a scale of one inch and a half to a foot. Plate No 2, is a section, plan, or top view of one side of the frame, and of the machinery and its combination which constitutes my invention, and this is drawn on a scale of three inches to the foot. On this plan the red lines represent the lines trace the friction roller a. the shank b. the joint c, and the bar d, in their position before the pull is commenced and the black lines represent them when the pull is finished at the point where the impression is completed.

This plan represents the whole of my invention which is described as follows: A. represents a section of one side of the common frame of the printing press, to which the side by which the operator stands: and is thus represented as the most convenient mode of showing how my combination of machinery is connected with it. B. represents an arm of cast iron or other substance, fastened on to the side of the frame, on the back side of, and even with, the section A. by four screws, of which two by the upper side of the arm are shown at d. d. and the two others are below them near the lower side of the arm and not visible in the figure.

This arm must be of sufficient depth & thickness to form a bearing at the joint b. sufficient to sustain the operation of the machinery. C. represents a piece of cast iron or other substance, either cast out or made up & bolted, fastened on to the side of the frame of which a section is represented at A. The use of this is to form a bearing in opposition of and in addition to the space against the frame

1151

for the friction roller a... also the main frame b... which is represented on the plan, since this projection is also the space for the friction roller a... on the frame as a plane, and this will probably be found the most convenient form. But I have found that surface & it may be varied on my principle by its being curved (either way) on the projecting part or across the frame. & in this whole contrivance that the friction roller b... it may proceed on a plane or on a curve, varying in any and every desired manner as experience or the taste of the operator may require, to render the pull uniformly equal or to adapt the required strength in the last pipe to the power to the efforts of the operator. D represents the pitman or driving lever which bears upon the projecting lever. This pitman lever or bar has nothing more in its formation, but in any combination, it is driven on to the projecting lever nearly in a right line with its motion while it proposes to effect the impression, and in this consists one of the advantages of my invention. E represents a strong bar or link proceeding from the joint b. to the joint e. It is a shank or extension of the working lever, turning nearly at right angles from the handle part of it at the moving joint b. and receiving at the end of it the friction roller a... G. is the working lever made of wrought iron or other suitable substance. It is a piece that is having a slot on the end of the working lever of a suitable size for the operator's hand. It is a part of the lower division of the projecting lever, with a socket to receive the end of the pitman. At the upper part of the piece l. is the tangent of the projecting lever. n represents the friction roller and being moved by the motion of the working lever it proceeds on the plane or other surface before described, it projects the joint e. & gives motion to the pitman which is connected with the joint e. h. represents a stationary joint

at the end of the arm B, which receives and sustains the bar
B. C. or another and a moving joint which connects the other
end of the bar B with the working lever at the point where
the shank D commences. By means of this combination,
where the working lever is moved from its place of rest as repre-
sented by the red lines to the point where the pull is finished
as represented by the black lines, the friction roller is
moved from its place as seen in the red lines, to the place
shown in the black lines, and thus gives the whole desir-
ed motion to the platen and completes the improvement.
d. d. represent two tips of the screws by which the arm
B is secured on to the section of the frame A, repre-
sents a triangular piece cast on to or otherwise secured
to the side of the link or bar B next to the arm B.
It is to terminate the pull at the desired point
and also to check the power and operation of the springs
which raise the platen. In testimony that the above
is a true specification of my said invention or
improvement as above described I have hereunto set my
hand & seal this ninth day of July in the year of our
Lord one thousand eight hundred and thirty one.

Witnessed
